Primary Examiner — Karen S Acker*Assistant Examiner* — Steven B Reinholdt, Jr.(57) **CLAIM**

The ornamental design for an optical sight, as shown and described.

DESCRIPTION

FIG. 1 is a front perspective view of an optical sight according to this disclosure;

FIG. 2 is a back perspective view of the optical sight of FIG. 1 according to this disclosure;

FIG. 3 is a top view of the optical sight of FIG. 1 according to this disclosure;

FIG. 4 is a right side view of the optical sight of FIG. 1 according to this disclosure;

FIG. 5 is a left side view of the optical sight of FIG. 1 according to this disclosure;

FIG. 6 is a front end view of the optical sight of FIG. 1 according to this disclosure; and,

FIG. 7 is a back end view of the optical sight of FIG. 1 according to this disclosure.

Broken lines in FIGS. 1, 2, 6, and 7 depict portions of the optical sight that form no part of the claimed design.

1 Claim, 7 Drawing Sheets(56)
